UNITED STATES PATENT OFFICE.

JAMES F. DUFFY, OF CHICAGO, ILLINOIS.

DESIGN FOR A HATCHET-HEAD.

SPECIFICATION forming part of Design No. 33,137, dated August 28, 1900.

Application filed July 23, 1900. Serial No. 24,611. Term of patent 7 years.

o all whom it may concern:

Be it known that I, JAMES F. DUFFY, a citizen of the United States of America, residing at Chicago, in the county of Cook and State of Illinois, have invented and produced a certain new and original Design for Hatchet-Heads, of which the following is a specification.

The drawing represents the design by means of a perspective view showing one face of the hatchet-head and the side adjacent to the handle.

Referring to the drawing, A is a substantially straight and thick portion having a comparatively-thin tongue B extending from it longitudinally of the hatchet and perforated at $b b' b^2$. From the thick straight portion A is a broadened comparatively-thin por-

tion C, notched at c on the edge and at c' on the end. From the opposite end of the portion A extends a bifurcated portion D substantially at right angles to the portion A.

The essential portion of my design I consider to be the comparatively-thick portion A, thinned and broadened into the portion C, notched at c c', the reduced tongue portion B, and the bifurcated portion D upon the opposite end of the portion A.

I claim as new and desire to secure by Letters Patent—

The design for a hatchet-head, substantially as shown and described.

JAMES F. DUFFY.
